SLINGSHOT FRAME

Max R. Cooley, 2721 W. 18th St. N., Wichita, Kans.

Filed May 28, 1964, Ser. No. 80,203

Term of patent 14 years

(Cl. D34—15)

FIGURE 1 is a perspective view of a slingshot frame showing my new design;

FIGURE 2 is a perspective view of the design of FIGURE 1 taken from the rear and left side;

FIGURE 3 is a side elevational view of the design of FIGURE 1 taken from the left side, and

FIGURE 4 is a front elevational view of the design of FIGURE 1.

The broken lines indicating a pouch and elastic assembly are for illustrative purposes only, and are shown fragmentarily in some figures for convenience of illustration.

I claim:

The ornamental design for a slingshot frame, substantially as shown and described.
